Leominster, Mass., a corporation of Massachusetts

Application August 20, 1948, Serial No. 148,206

Term of patent 14 years

(Cl. D74—24)

To all whom it may concern:

Be it known, that I, Bernard Ulvad, a citizen of the United States, residing at Leominster, in the county of Worcester, State of Massachusetts, have invented a new, original, and ornamental Design for a Crayon or the Like, of which the following is a specification, reference being had to the accompanying drawing, forming part thereof, in which:

Fig. 1 is a side elevational view of a crayon or the like, showing my new design;

Fig. 2 is a side elevational view of the opposite side shown in Fig. 1; and

Fig. 3 is a front elevational view thereof.

I claim:

The ornamental design for a crayon or the like, substantially as shown.

BERNARD ULVAD.
